(57) **CLAIM**

I claim the ornamental design for an adjustable perimeter slider track for mounting wall panels onto an existing wall, as shown and described.

DESCRIPTION

FIG. 1 is a perspective view of the adjustable perimeter slider track for mounting wall panels onto an existing wall, showing front, left and bottom sides in accordance with the present design;

FIG. 2 is a perspective view showing right, front and top view thereof;

FIG. 3 is a left side elevational view thereof with the right side elevational view being a mirror image thereof;

FIG. 4 is a bottom plan view thereof;

FIG. 5 is a top plan view thereof;

FIG. 6 is a front elevational view thereof; and,

FIG. 7 is a back elevational view thereof.
